UNITED STATES PATENT OFFICE.

BENJAMIN D. HARRIS AND CHARLES R. BURTON, OF ST. LOUIS, MISSOURI, ASSIGNEES
OF ONE-THIRD TO PATRICK H. CULLEN, OF ST. LOUIS, MISSOURI.

TICKET PUNCH.

Application filed February 23, 1924. Serial No. 694,467.

To all whom it may concern:

Be it known that we, BENJAMIN D. HARRIS and CHARLES R. BURTON, citizens of the United States of America, residing at the city of St. Louis, in the State of Missouri, have invented certain new and useful Improvements in Ticket Punches, of which the following is a specification, reference being had therein to the accompanying drawing.

Our invention relates to improvements in ticket punches and has for its object to provide a punch capable of consecutively numbering the tickets punched, perforating said tickets with a conductor's personal identification mark, permitting said conductor's personal identification die to be used independently of the number-punching mechanism, and having an additional cut-out punch (for cutting out numbered squares from commutation tickets) with means for collecting the cut-out sections in a locked compartment, for auditing purposes.

The tool of our invention is in aid of the checking and auditing departments of the carrier in whose service said tool is employed, and is primarily intended to consecutively number the tickets collected on each run, and from run to run, while leaving the conductor's individual punch-mark capable of being operated independently of such numbering mechanism, to the end that it may be used in marking hat-checks and the like. The cut-out mechanism is devised and intended for commutation tickets only, the auditor's check being effected from the cut out ticket-sections, collected in a locked compartment for that purpose; such commutation tickets being checked by means of the ticket fragments collected in such compartment, the key to which is held by a person other than the conductor.

Drawings.

In the drawings—

Fig. 1 is a side elevation of a punch embodying our invention.

Fig. 2 is a top plan view of the same.

Fig. 3 is a front elevation of the same.

Fig. 4 is a plan view of a commutation ticket illustrating the work to be done by the side or block-out punch.

Fig. 5 is a plan view of a train ticket punched by the numbering apparatus and conductor's individual or signature punch element of our punch.

Fig. 6 is a longitudinal vertical sectional view of the punch of our invention taken on the line 6—6 of Fig. 2.

Fig. 7 is a transverse vertical sectional view of the same, taken on the line 7—7 of Fig. 2.

Fig. 8 is a similar view taken on the line 8—8 of Fig. 6.

Description.

As illustrated, the punch of our invention comprises the opposed upper box-jaw 10 and lower box-jaw 11, actuated by the handle-members 12 and 13. Near the outer extremities of said jaws are the male member 14 and female member 15 of the conductor's individual punch.

The numbering apparatus A consists of an upper and male series of numbering disks 16, mounted in the upper jaw 10, and an opposed female series of disks 17 co-operating with said disks 16 and seated in the lower jaw 11.

To enable the conductor's individual punch (members 14 and 15) to be used otherwise than in conjunction with the numbering apparatus A we have provided a transverse control-rod 18 having the push buttons 19 and 20 upon its opposite extremities, as shown in Figs. 7 and 8, the function of which rod is to disconnect the numbering apparatus A so that it will be inoperative when the handles 12 and 13 are manipulated for purposes not requiring the use of such numbering apparatus.

As shown in Fig. 6 the series of male numbering disks 16 is mounted on the shaft 21, female series 17 being mounted on the shaft 22. The series 16 terminates in a ratchet wheel 23 which is driven from the shaft 22 by means of the pawl 24. Similarly, the disk series 17 is provided with the ratchet wheel 25 driven from the shaft 21 by the pawl 26. To render the ratchet wheels 23 and 25 inoperative, we provide a pin 27 carried by a standard 28, which standard 28 is fixed upon the rod 18; the pin 27 when thrust toward the left as shown in Fig. 8, by a pressure upon the push-button 20, will throw both of pawls 24 and 26 out of engagement with their respective ratchet wheels, thus rendering the numbering apparatus A idle.

Our punch also has the cut-out or block-out die 29 mounted as shown, to punch out

the numbered squares commonly used upon the margins of commutation tickets; the numbered fragments as they are cut by the die 29 are forced through the mouth 30 into the chamber 31. The chamber 31 is normally locked closed by means of a lock 32, which is unlocked for the purpose of auditing the ticket-fragments.

Mode of operation.

In the use of our ticket punch the conductor treats the tickets collected in the manner now common, punching out numbered squares from commutation tickets, and perforating all other tickets with his individual punch. But in using our punch he also, when applying his individual punch-mark, simultaneously perforates the tickets with a serial number. The purpose of that serial number is to enable an inspector or auditor to check up the result of the conductor's run, requiring the production of the tickets in their proper numerical sequence, thus safeguarding against tickets being held over by the conductor from one run, and turned in as against a later run.

The conductor also uses the individual punch for hat-checking and other purposes, and accordingly we provide means for disconnecting the numbering apparatus A as above described.

Claims.

We claim—

1. In a ticket punch in combination a consecutive-numbering apparatus and an identification punch; a hand-actuated means for simultaneously actuating said numbering ap-

paratus and identification punch; and means for disengaging said numbering apparatus to permit the independent operation of said identification punch.

2. A ticket punch comprising two hand-lever-actuated jaws; a series of numbering disks and an identifying die mounted in one of said jaws; a corresponding series of co-operating disks and a female member for said identifying die mounted in the opposing jaw; and means for disengaging said disks from actuation by said hand-lever.

3. In a ticket punch in combination a consecutive-numbering apparatus and an identification punch; a hand-actuated means for simultaneously actuating said numbering apparatus and identification punch; and means for disengaging said numbering apparatus to permit the independent operation of said identification punch; together with a cut-out punch, and a receptacle for the cuttings formed by said cut-out punch.

4. A ticket punch comprising two hand-lever-actuated jaws; a series of numbering disks and an identifying die mounted in one of said jaws; a corresponding series of co-operating disks and a female member for said identifying die mounted in the opposing jaw; and means for disengaging said disks from actuation by said hand-lever; together with a cut-out punch, and a receptacle for the cuttings formed by said cut-out punch.

In testimony whereof we have hereunto affixed our signatures.

BENJAMIN D. HARRIS.
CHARLES R. BURTON.
